UNITED STATES PATENT OFFICE

130,227

DESIGN FOR A HAT

Paul M. Maxwell, Manhasset, N. Y., and Wilhelmina J. Russy, Jersey City, N. J., assignors to Hat Corporation of America, Norwalk, Conn., a corporation of Delaware

Application July 10, 1941, Serial No. 102,012

Term of patent 3½ years

To all whom it may concern:

Be it known that we, Paul M. Maxwell and Wilhelmina J. Russy, citizens of the United States, residing, respectively, at Manhasset, county of Nassau, and State of New York, and at Jersey City, county of Hudson, and State of New Jersey, have invented a new, original, and ornamental Design for a Hat, of which the following is a specification, reference being had to the accompanying drawing, forming a part thereof, and in which:

Fig. 2 is a top plan view of the hat shown in Fig. 1.

Fig. 3 is a left-hand side view of the hat shown in Fig. 1.

Fig. 4 is a bottom plan view of the hat shown in Fig. 1.

We claim:

The ornamental design for a hat, as shown.

PAUL M. MAXWELL,
WILHELMINA J. RUSSY.
